(57) CLAIM

The ornamental design for a lighted address structure for houses or the like, as shown and described.

DESCRIPTION

FIG. 1 is a perspective view of the present invention;

FIG. 2 is a front view of the present invention;

FIG. 3 is a left side view of the present invention;

FIG. 4 is a right side view of the present invention;

FIG. 5 is a back view of the present invention;

FIG. 6 is a top view of the present invention; and,

FIG. 7 is a back view of the present invention.

The broken lines in the drawings depict environmental structure, which forms no part of the claimed design.
